[57] CLAIM

The ornamental design for a cereal bowl, as shown and described,

DESCRIPTION

FIG. 1 is a perspective view of a cereal bowl showing my new design;

FIG. 2 is a side view, the opposite side view being identical;

FIG. 3 is a top plan view;

FIG. 4 is a bottom plan view;

FIG. 5 is an end view, the opposite end view being identical; and,

FIG. 6 is a perspective view of another, rectangular embodiment of the cereal bowl.

The undisclosed top, bottom and elevational views of the rectangular embodiment are identical to those of the oval embodiment with the exception of the differences created by the change from an oval shape to a rectangular shape.
